UNITED STATES PATENT OFFICE.

JOSEPH J. WHITE, OF NEW LISBON, NEW JERSEY, ASSIGNOR TO HIMSELF AND HOWARD WHITE, OF TULLYTOWN, PENNSYLVANIA.

IMPROVEMENT IN FARE-BOXES.

Specification forming part of Letters Patent No. 150,500, dated May 5, 1874; application filed April 4, 1874.

To all whom it may concern:

Be it known that I, JOSEPH J. WHITE, of New Lisbon, in the county of Burlington and State of New Jersey, have invented a new and useful Improvement in Fare-Boxes, of which the following is a specification:

This invention relates to apparatus for collecting passenger fares on rail-cars; and consists of a cash-box supported from the waist or shoulders of the conductor, to which is attached a flexible tube, having at its end a hand-piece or receiving-box containing an endless carrier, which is arranged on pulleys, so as to be moved, by means of a ratchet and pawl operated by a spring-lever, by the conductor, the construction being as hereinafter more fully described.

In the accompanying drawing, Figure 1 represents a longitudinal section. Fig. 2 is a section of the hand-piece, showing the details.

Similar letters of reference indicate corresponding parts.

A is a box, made in any convenient form, of wood, sheet metal, or any suitable material, which is suspended from the person of the collector. This is the cash-box to which the fares are conveyed from the receiving-box or hand-piece B, by means of a belt or carrier, C, contained in the flexible or metallic hinged tube D. This belt C is endless, and passes around a pulley at each end, one pulley, E, being located in the cash-box, and the other pulley, F, being in the hand-piece B. Each fare is dropped into the hand-piece B (as it is received) through the orifice G, and is received on the carrier-belt C. On the shaft of the pulley F is a ratchet-wheel, H, which is revolved by means of the spring-pawl I on the pivoted arm J, actuated by the spring-lever K on the under side of the hand-piece. L is a spring-pawl, which works in the ratchet to prevent back motion. As the fare drops onto the belt the conductor draws the spring-lever up to the tube, which causes the belt, pulley, and ratchet

to make a part of a revolution, and to move the belt and fare a short distance toward the cash-box A. M are little buckets or carriers on the belt. N is a bell which, by means of a hammer actuated by the lever, is made to ring and give notice whenever a fare is received or whenever the lever is operated.

The conductor or collector carries the hand-piece B in his hand, and, by virtue of the flexible tube and belt, he is enabled to pass it round among the passengers to receive the fares.

The orifice G is in a projecting portion, O, of the hand-pieces, which portion may be partly composed of glass, to allow the collector to see if the right fare has been deposited; but the fare may be deposited in the hand-piece B by the conductor himself, the main advantage being that it does not go into his pocket, but is conveyed to the cash-box A, which is secured by a lock at the office before he starts on his trip.

P is a suspender-strap attached to the cash-box. Q is a valve or flap for protecting the fare.

Having thus described my invention, I claim as new and desire to secure by Letters Patent—

1. A portable fare-box having a carrying belt or chain for conveying the fare from its receiving orifice to its depository, arranged substantially as shown and described.

2. The receiving-chamber connected with the fare-depository by a flexible or hinged tube, substantially as shown and described.

3. A portable fare-box, having its receiving-chamber and fare-depository connected by a flexible or jointed tube, and with a conveying-belt, arranged to operate substantially as shown and described.

JOSEPH J. WHITE.
